US0D1053909S

(12) **United States Design Patent** (10) **Patent No.:** **US D1,053,909 S**
(45) **Date of Patent:** **** Dec. 10, 2024**

(54) **NETWORK VIDEO RECORDER**

(71) Applicant: **Shenzhen Raycloud Technology CO., Ltd.**, Shenzhen (CN)

(72) Inventor: **Shengjun Li**, Shenzhen (CN)

(73) Assignee: **Shenzhen Raycloud Technology CO., Ltd.**, Shenzhen (CN)

(**) Term: **15 Years**

(21) Appl. No.: **29/893,758**

(22) Filed: **Jun. 2, 2023**

(51) LOC (14) Cl. **14-03**

(52) U.S. Cl.

USPC **D14/496**

(57) **CLAIM**

The ornamental design for a network video recorder as shown and described.

DESCRIPTION

FIG. 1 is a front, right and top perspective view of a network video recorder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the network video recorder that form no part of the claimed design.

1 Claim, 8 Drawing Sheets
